UNITED STATES PATENT OFFICE

GEORGE W. GILL, OF BATTLE CREEK, MICHIGAN, ASSIGNOR TO WALTER E. KNOPP, OF BATTLE CREEK, MICHIGAN

VALVE IN HEAD DOUBLE ACTION BELL RINGER FOR LOCOMOTIVE ENGINES

Application filed March 23, 1927. Serial No. 177,550.

The present invention relates to automatic bell ringers for steam locomotives.

Automatic bell ringers of the nature set forth, to the best of my knowledge and belief, do not properly function at all times, respecting a predetermined movement for oscillating the bell yoke. Ringers of this character often permit a bell to careen, destroying the rhythm of the bell tone, twisting the bell rope, and destroying its use for the purpose, and entailing expense for its replacement. The present invention has for its purpose to overcome these disadvantages, and to provide a bell ringer that, barring accidental breakage and wear, will always properly function.

A characteristic feature, and important object of the present invention is a valve, having an elongated venti-duct stem, opening below a tapering elongated head thereof; said head being operable in a tubular seat suspended from a casing, forming an air chamber above, and about the upper end of said cylinder, said valve adapted to receive air from said chamber when its elongated stem is pushed upward by an upper thrust of the piston operable in said cylinder, striking said stem unseating said valve, and admitting air from said chamber to react said piston automatically.

My invention has for its main object to so construct a fluid pressure operated bell ringer, whereby the upward movement of said bell will be limited by a cushion of air controlling the piston, and pitman connected with the bell crank.

Another object of my invention, is to so construct a mechanism for the purpose, whereby the stroke of the operating piston will always be uniform; still another object is to so construct a device for the purpose, whereby the piston will automatically seal, and unseal its intake, and exhaust ports during operation. Other objects include staunchness in construction, simplicity, durability, neatness in design, and economy to produce.

In the drawings forming a part of these specifications, Fig. 1 is a longitudinal side elevation of my improved bell ringer in

cross-section, showing the bell at idle, the operating piston at the bottom of its stroke, the intake port to the cylinder open, and the exhaust port closed.

Fig. 2 is a similar view to Fig. 1, except, in this view the bell is being carried on its upward movement and the piston is at the limit of its upward power stroke and the intake port is closed, and the exhaust port is opened.

Fig. 3 is a similar view of Fig. 1, with the bell thrown to its uppermost limit of movement, the exhaust port remaining open, and the valve-in-head raised to admit live air for cushioning the piston and preventing the bell from overturning.

Fig. 4 is a detail side view of the bell bracket and the bell operative crank and pitman.

Fig. 5 is a side elevation of the air cylinder.

Fig. 6 is a cross section of the air cylinder head on the line A. B. of Fig. 3.

Fig. 7 is a plan view of Fig. 5.

Fig. 8 is an enlarged view of Fig. 2, with the floating ring shown in cross-section, and Fig. 9, is a cross-section of Fig. 8, below the line L. D.

In the drawings like marks of reference refer to corresponding or equivalent parts in the different views in which, C is an air cylinder casing; D, its upper head; E, a bell suspended in yoke; F and G, the bell yoke bracket.

In the views the bell is shown as poised to swing on the side opposite to its operating cylinder.

The cylinder, in the main, comprises a cast metallic casing C, closed at its lower end and capped by a chambered centrally apertured head D, between the parts of which an apertured gasket 1, is interposed and the parts held in place by means of cap screws 2, in the customary manner. The upper half of the cylinder casing is formed with an enlarged bore, and this enlarged portion forms a concentric chamber 3, spaced from the main chamber 4 of the cylinder by a bushing 5, extending from near the lower head of said cyl-

inder to a line on the plane with the top of said casing.

Within the cylinder a spool-shaped piston 26, is placed the upper head of which carries a series of sealing rings in the usual manner, the lower head being made to slide freely and without sealing.

Leading into the lower portion of the concentric air space 3, a pipe for air connects by means of a nipple 6, of the cylinder.

The head D, forms an air tight chamber at the upper cylinder end, and is secured to the cylinder casing, C by means of cap screws 2, passing through a peripheral flange of said head, and into a complementary flange about the end of said casing as shown.

Between the head D, and the casing C, and also between the upper end of the bushing 5, and the concentric interior portion 9, of said head, an air tight gasket 1 is placed. At points in said gasket, apertures 15 connect the chamber 3 of the cylinder with the chamber 16 of the head D.

Centrally of the head D, a neck 10 connects with the part 9, and through said parts a bushing 12 is fitted, and through which the piston rod 13 operates. The bushing aforesaid is formed with a series of elongated grooves 14, (See Figs. 6 and 8) which open into the piston chamber of the cylinder at their ends, but do not extend to the upper end of said bushing, as will hereinafter be more fully explained.

To one side of the piston bushing, and piercing the head D, and its interior portion 9, the parts are bored and fitted with a thimble 17, and a bushing 18, respectively; the thimble 17 forming a guide for the head of the intake valve 19, the bushing 18 providing a guide and seat for said valve.

This valve below its head is an elongated tube opening at its juncture with its tapering seat, through small apertures, not shown, and at its lower end, and when seated seals the chamber 16 from the cylinder. The unseating of said valve is effected by an upper movement of the seated or ring portion of the piston in the operation of device, as will be hereinafter more fully explained.

In Figs. 1, 2, and 3, side elevations of the cylinder piston are shown in various operative positions. This piston is very similar to others of a spool type, and has spaced-apart heads 20 and 21, the upper head carrying sealing rings 22.

Occupying a position between the heads of the piston a diagonally served floating ring 23 frictionally bears against the wall of the cylinder. This ring is of a length sufficiently long to always cover one or the other of the intake, or exhaust ports, 24 and 25 respectively, it being considerably narrower than the space between the piston heads, which in the movement of said piston move said ring to cover and uncover said ports; as for in-

stance when said piston is at its lowermost position in the cylinder, said ring will occupy a position immediately below the intake port 24, as shown in Fig. 1, at which position the exhaust port 25 will be closed by the floating ring 23, and the intake port 24 will be opened.

As will be noticed when the piston is at its lowermost position in the cylinder the chamfer 26 on the under side of the upper head of the piston registers with the intake port 24, whilst at its uppermost position the chamfer 27 on the upper side of the lower piston head registers with the exhaust port 25, permitting the air or fluid between the heads to escape.

In Figs. 2 and 3, the lower heads 21, of the piston is shown over the exhaust port 25, and it would be obvious that a downward movement of the piston would be cushioned by imprisoned fluid in the cylinder below the exhaust port 25 were no provision made to prevent said cushioning. This cushioning effect is avoided by a slight looseness between the lower head of the piston and the cylinder wall and by further providing a cross groove 32 in the lower head of said piston adapted to register with said port.

As heretofore disclosed both piston heads are chamfered or have cut-away portions 26 and 27, which at predetermined operating movements of said piston, register with the intake and exhaust ports of the cylinder. The ports 24 registering with the chamfer 26 on the under side of the upper piston head; the chamfer 27 being on the upper edge of the under piston head as shown. These chamfers or notches are of a size sufficiently proportioned to permit air to enter and leave the cylinder between the ring 23 and a piston head, when the latter is moved into contacting position and one or the other of said ports register herewith, examples of which are shown in Figs. 1, 2 and 8.

Referring again to the grooves 14 in the bushing 12, these grooves are positioned in such manner that when the piston rod 13 is near its lower position sealing rings 28, seated in annular grooves in said rod will be moved into a position between the ends of said grooves, and permit air within the cylinder, above the upper piston head, to flow by said sealing rings and escape into the atmosphere through the gland 12 and the piston rod as shown in Fig. 1; the looseness between said rod and its gland allowing for air to thus escape.

As shown in Figs. 1 and 2 the intake valve 19 is seated and will not permit air under pressure to enter the upper chamber of the cylinder.

Having in the main described the construction of my improved bell ringer, I will now explain its operation. Air having been directed to the cylinder through a suitable conduct connecting with the nipple 6, it will flow into the concentric chamber 3, and fill

the chamber surrounding the upper head D thereof.

Assuming the bell to rest or idle, as shown in Fig. 1; air will flow between the ring 23, and the upper piston head from the chamber 3 and into space between the piston heads; as the exhaust port 25 is sealed by said ring 23, and the sealing rings 28 about the piston rod as positioned to permit air in the upper portion of the cylinder to pass out through the grooves 14, the piston will be carried upward, carrying the bell to its upper stroke as shown in Fig. 3. As will be noticed in this particular view, the bell is carried to its uppermost position with the crank pin 29 at the outer end of the slot 30, in the pitman 31, at which position the upper thrust of the pitman has stopped, and the thrust imparted from the stroke of the piston had been curtailed by a cushion of air entering the cylinder through the valve-in-head 19. Air having entered the cylinder through said valve, the opening of which had been affected by the piston elevating to unseat the same, and the sealing of the cylinder by the rings 28 on the piston rod closing the gland or bushing 12, the gravity force of the bell on its downward movement will return said piston; it being understood that during the movement of the piston in its upward thrust the sealing ring 23 between the piston heads has also been carried upward by the piston head 21 unseating the exhaust port 24, preparing the piston for a downward movement in said cylinder by a downward movement of said bell and connective parts and the fluid having entered the piston chamber via the valve 19.

In Fig. 3, the piston is shown as having carried the sealing ring 23 beyond the exhaust port 25, and leaving the lower piston head over said port. Such condition is caused by the momentum imparted to both the bell and piston, by the inrush of air, but owing to the counter balance, effected by air entering the upper chamber to the cylinder through the valve-in-head 19, the piston, together with the bell will be prevented from further upward movement, yet unrestrained in its downward throw.

The arrangement of the parts is such that should it be necessary to turn the bell over by hand when idle, and not limited by the cushion of air entering the cylinder through the valve 19, in other words when air is cut off from entering the air cylinder, the piston 26 will raise within the cylinder sufficiently to permit the pitman 31 to let the bell carry over. In Fig. 3 is shown the limit of the upward movement of a bell when cushioned to prevent further upward and over movement of the same. In this view is also shown sufficient open space between the cylinder head and the piston to permit its connection with said bell, to turn over, should occasion arise,

when air under pressure has been cut off from entering the cylinder.

From the foregoing description, the objects, general utility, and advantages of my invention, it is believed, will have been fully comprehended.

Having therefore set forth my invention, what I claim as new and desire to secure by Letters Patent is:—

1. In a device of the class set forth the combination of a cylinder having two chambered compartments, one compartment comprising a piston chamber, the other compartment constituting an air supply chamber surrounding said piston chamber for a portion of its length and its head at one end, a reciprocative piston operable in said piston chamber and having a piston stem operable through a gland extending through said air supply chamber, said cylinder having an air inlet into said air chamber and an exhaust port leading into said piston chamber near its end opposite from said gland and an intake port leading from said air chamber into said piston chamber approximately its center and a gland opening through said head between said air chamber and piston chamber, a valve operable through said gland, amenable to admit air from said air chamber into said piston chamber by an upward contact of said piston with said valve and cushion a further upward movement of said piston, said valve seating by gravity action, said piston adapted to be moved toward and into contact with said valve by the admission of air through said intake port, said gland about said piston stem forming an exhaust port for that end of said piston chamber through means carried by said stem to alternately seal and unseal said gland at predetermined movements of said piston and valve.

2. In a device of the class set forth, the combination with a cylinder, a piston operative in said cylinder, an encompassing supply chamber for said cylinder hermetically sealed therefrom, but communicative therewith through a port governed by the action of said piston, a piston rod extending from said piston through a gland leading through said supply chamber, a tappet valve through the wall between said supply chamber and said cylinder, a tappet valve operative in said opening a thimble forming a guide for the head of said valve in the outer wall of said supply chamber, said valve adapted to admit air from said supply chamber into said cylinder by the uplift of said valve by said piston, and means including grooves in said gland and sealing rings on said piston rod to alternately open and close said gland for the purpose of compression and exhaust, during the operation of said piston and said valve substantially as set forth.

3. In a device of the class set forth, the

combination of a cylinder having two compartments, one of said compartments comprising a piston chamber the other of said compartment constituting a concentric chamber 5 about the upper end of said piston chamber, and a portable head portion over and about said cylinder portion, said head portion having a central neck and a connective flange adapted to seat on and close the upper 10 end of said piston chamber, a gasket interposed between the end of said piston chamber and said flange and adapted to also lie between the outer wall of said head and the upper end of said concentric compartment, 15 means including apertures through said gasket to permit fluid to freely flow from said concentric compartment into said head, means to detachably secure said head to said piston chamber and said concentric compartment, 20 a spool piston operable in said piston chamber and having a piston rod extending through an opening in said neck portion, said piston being actuated by fluid pressure from said outer compartment through an 25 intake port into said piston chamber and a valve controlled port between said head and said piston chamber, a tappet valve operable in said valve controlled port, a frictional contact ring carried in said piston chamber 30 between the heads of said piston, said piston chamber having an exhaust port, said tappet valve being closed antecedent to an upward movement of said piston thereagainst, said intake and exhaust ports being alter- 35 nately opened and closed by said floating ring, the former port being closed antecedent to said piston engaging said tappet valve and the latter port being opened, and means to release fluid pressure above said piston in 40 said piston chamber to said piston opening said tappet valve.

4. In a device of the nature set forth, the combination of a cylinder having two compartments including a chambered head, one 45 of said compartments forming an outer chamber concentric with the upper end of a central piston chamber, said chambered head having an outer wall adapted to seat on the upper end of said outer chamber, said head 50 having an inner concentric centrally apertured neck with a depending disc-shaped end, said disc-shaped end adapted to seat on the upper end of said piston chamber, a spool piston operable in said piston chamber and 55 having a piston rod adapted to operate through said centrally apertured neck of said head, said disc-shaped end of said neck portion having a gland opening connecting said piston chamber with the chambered por- 60 tion of said head, said piston chamber having an intake port connecting with said outer chamber near the lower end of said outer chamber and an exhaust port near the lower end of said piston chamber, a fric- 65 tional contact floating ring carried between

the heads of said piston adapted to open and close said intake and exhaust ports, in its reciprocal movement within said piston chamber, a tappet valve operable through the gland of said disc-shaped end, said gland 70 being closed by said tappet valve when said piston recedes from contact therewith, and opened to admit fluid pressure from said outer chamber, when said piston is at its uppermost position, and means to release compression between said valve and the upper head of said piston subsequent to said head engaging said valve.

GEORGE W. GILL.
